CLAIM

The ornamental design for a troffer assembly with cylindrical extensions, as shown and described.

DESCRIPTION

FIG. 1 is a perspective view of a troffer assembly with cylindrical extensions showing my new design;

FIG. 2 is a bottom plan view thereof;

FIG. 3 is a top plan view thereof;

FIG. 4 is a side view thereof. The opposite side is a mirror image thereof; and,

FIG. 5 is a front elevation view thereof. The rear elevation view is a mirror image thereof.

The broken lines illustrate portions of the device that form no part of the claimed design.
